UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,909, dated November 14, 1893.

Application filed October 9, 1893. Serial No. 487,875. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of Colonial style of ornaments placed at equal distances apart over the surface of the paper as represented in the accompanying drawing. The border or upper portion of the design is formed of the same ornaments connected by ornamental scrolls as shown forming a continuous border.

What I claim is—

1. The design for wall paper herein shown and described.

2. In the design for wall paper, the border herein shown and described.

Witness my hand this 5th day of October, 1893.

CHARLES BOOZE.
